UNITED STATES PATENT OFFICE.

GEORGE THOMAS BUCKHAM, OF WESTMINSTER, LONDON, AND FRANK SMITH, OF WOLVERHAMPTON, ENGLAND, ASSIGNEES TO VICKERS LIMITED, OF WESTMINSTER, ENGLAND.

MACHINE-GUN CARRIAGE.

1,289,641.

Specification of Letters Patent. Patented Dec. 31, 1918.

Application filed October 9, 1915. Serial No. 55,122.

To all whom it may concern:

Be it known that we, GEORGE THOMAS BUCKHAM and FRANK SMITH, both subjects of the King of Great Britain, residing, respectively, at Vickers House, Broadway, Westminster, in the county of London, England, and Pelham street, Wolverhampton, in the county of Stafford, England, have invented certain new and useful Improvements in or Relating to Machine-Gun Carriages, of which the following is a specification.

This invention relates to cycle side-cars adapted to carry automatic guns.

According to this invention we so construct and arrange the side-car that an automatic gun together with its tripod mounting can be supported thereon in one or other of two positions, so that the gun can fire either in a forward or a rearward direction as required. For this purpose the side-car may have two bed plates or supports one arranged at the forward and the other at the rear part of the side-car; these bed plates are adapted to receive the tripod mounting so that in changing the position of the gun, the mounting and the gun as a whole can be moved from one bed plate or support to the other. The said bed plates or supports may be provided with quick release catches.

The seat for the gunner is movable or adjustable so as to suit either of the two positions of the gun, and for this purpose may be carried on a swing framework, attached to a vertical pivot about which it may be swung. This vertical pivot is so placed that the seat assumes two different positions suitable for enabling the gunner to fire in either direction, the seat being the same distance from the breech end of the gun in each case. The framework for the seat may be provided with a stop which serves as a support for the base of the tripod leg.

In order that the invention may be clearly understood and carried into effect the same will now be described more fully with reference to the accompanying drawing, in which:—

Figure 1 is an elevation of a motor cycle provided with a side car constructed according to the invention, the gun and gunner's seat being shown in full lines for firing in the direction in which the cycle is traveling,

and in dot-dash lines for firing in a rearward direction.

Fig. 2 is a plan of the cycle and side-car with the gun removed in order to show the disposition of the bed plates or supports for the gun.

Fig. 3 is a front view and Fig. 4 is a detail view showing the manner of swiveling the gunner's seat.

A and B, are the horizontal bed plates or supports of approximately triangular formation located respectively at the forward and rearward portions of the side car frame. C are the quick release catches carried by the bed plates said catches being adapted to engage with the mounting D of the gun so as to hold it firmly in position. The said quick release catches C are constructed and adapted to operate in the manner set forth in United States application, Serial No. 55793. In placing the gun and its mounting in position on the front or the rear bed plate, the front legs a of the tripod (one of which is shown in Fig. 1) are first folded against the rear leg or trail b, straps being used if necessary to keep them in this position. The spade b' of the rear leg is caused to engage with a suitable abutment b' carried by the gunner's seat E', and the mounting D is lowered on to one of the aforesaid bed plates. The quick release catches C are then moved to the operative position and the gun is firmly secured to the bed plate and is ready to be transported by the side car and fired when in this position.

In order to detach the mounting to enable the gun to be moved from the front bed plate to the rear bed plate of the car, or vice versa, the above mentioned operations are reversed. It will be obvious that when the car is not traveling the gun and its tripod may be bodily removed and placed on the ground for firing. Ammunition trays E and foot rests F for the gunner are provided at the front and rear of the side car.

E' is the gunner's seat which is carried by the aforesaid swing framework; this framework has a horizontal pivot e' and a vertical pivot e'' about which the seat can be swung when changing from one position to the other for which purpose as shown in Fig. 4, the seat is first raised on its horizontal pivot e' and then swung about its vertical pivot e''.

Suitable provision may be made at the rear of the side-car to accommodate a frame structure F for carrying ammunition, water, spare parts, and tools. This frame structure, which forms no part of the present invention, may be supported from the side-car by suitable spring arrangements, so that the jolting of the frame structure and its contents, due to road shocks, will not be transmitted to the side-car.

At the front of the side-car are provided shields G, G' consisting of an upper and lower part. The lower part G' is rigidly attached to the side car while the upper part G is attached to the upper carriage of the gun and swivels with the same in training. The upper part of the shield, being attached to the upper carriage, is utilized for protecting the gunner when firing either to the front or to the rear.

What we claim and desire to secure by Letters Patent of the United States is:—

1. A cycle side car provided with means for supporting thereon an automatic or other machine gun together with its tripod in one or other of two positions so that the gun can fire either in a forward or a rearward direction as required.

2. A cycle side car provided with means for supporting thereon an automatic or other machine gun together with its tripod in one or other of two positions so that the gun can fire either in a forward or a rearward direction as required, a seat for the gunner and means for adjusting said seat to suit either of the two positions of the gun.

3. A cycle side car provided with means for supporting thereon an automatic or other machine gun together with its tripod in one or other of two positions for forward or rearward firing, a seat for the gunner, means for adjusting said seat to suit either of the two positions of the gun, and means for attaching said side car to a cycle.

4. A cycle side car provided with two bed plates or supports one at the front and the other at the rear part of the side car, and means for detachably securing an automatic or other machine gun, together with its tripod, to one or other of said supports for forward or rearward firing.

5. A cycle side car provided with two bed

plates or supports one at the front and the other at the rear part of the side car, means for detachably securing an automatic or other machine gun, together with its tripod, to one or other of said supports for forward or rearward firing, a vertical pivot carried by the side car, and a gunner's seat rotatably attached to said pivot so that it can be swung around said pivot to suit either of the two positions of the gun.

6. A cycle side car provided with two bed plates or supports one at the front and the other at the rear part of the side car, means for detachably securing an automatic gun, together with its tripod, to one or other of said supports for forward or rearward firing, a seat for the gunner, means for adjusting said seat to suit either of the two positions of the gun, and means carried by the framework of the seat for supporting one of the tripod legs in either of the two positions of the gun.

7. A cycle side car provided with two bed plates or supports one at the front and the other at the rear part of the side car, means for detachably securing an automatic or other machine gun together with its tripod to one or other of said supports for forward or rearward firing, a seat for the gunner, means for supporting said seat so that it can be swung horizontally through an angle of 180°, means carried by said seat for supporting one of the tripod legs in either of the two positions of the gun, and means for connecting said side car to a cycle.

8. A cycle side car provided with two bed plates or supports one at the front and the other at the rear of the side car, means for rapidly attaching or detaching an automatic or other machine gun together with its tripod to or from one or other of said supports, a seat for the gunner, and means for adjusting said seat to suit either of the two positions of the gun.

In testimony whereof we affix our signatures in the presence of two witnesses.

GEORGE THOMAS BUCKHAM.
FRANK SMITH.
